US00D483746S

(12) **United States Design Patent** (10) Patent No.: **US D483,746 S**
Hyogo (45) Date of Patent: **** Dec. 16, 2003**

(54) **RELAY MACHINE FOR WIRELESS DATA
COMMUNICATION**

(75) Inventor: **Kuninori Hyogo**, Tokyo (JP)

(73) Assignee: **Sony Corporation**, Tokyo (JP)

(**) Term: **14 Years**

(21) Appl. No.: **29/164,050**

(22) Filed: **Jul. 18, 2002**

(51) LOC (7) Cl. **14-03**

(52) U.S. Cl. **D14/240**; D14/230

PLLC

(57) **CLAIM**

The ornamental design for a relay machine for wireless data communication, as shown.

DESCRIPTION

FIG. 1 is a perspective view of a relay machine for wireless data communication showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
